Application January 27, 1953, Serial No. 333,494

9 Claims. (Cl. 122—479)

This invention relates to control systems and has for an object the provision of a system in which each of the magnitudes of two conditions which normally vary in dependent relationship may be regulated without substantial change of the other magnitude.

The present invention is particularly applicable to power generating systems of the type which include turbine-generators in which the steam after passing through one group of stages of the turbine is reheated and then passed through a second group of stages of the turbine. The steam, generally elevated to high temperatures and pressures, is discharged from superheater coils to the first section of the turbine. In developing a part of the power needed to turn the generator there is in the turbine a decrease in the temperature and pressure of the steam. It has been found that higher operating efficiencies may be attained by again heating the steam as by passing it through a reheater section of the boiler to elevate again its temperature and then passing the steam successively through the several stages usually present in a steam turbine.

In the generation of power, the trend has been to utilize high temperatures and high pressures to attain high efficiency. In addition, the maintenance of a constant temperature results in eliminating thermal expansion and contraction of the turbine components. However, as the temperatures and pressures have been increased, so has the importance of a control system which will insure operation below the danger point as regards the strength of the tubes and lines through which the steam passes. The nearer the temperature approaches that of the yield point of the tubes, the more important it is that the control system prevent rise of temperature into the danger zone. Accordingly, in furnaces in which steam superheater coils and steam reheater coils are both disposed in heat exchange with hot products of combustion from the fire chamber, it is apparent that there must either be provided separate control of the temperature of the steam in the outlet of each of the respective coils or one of them must be operated in manner such that its temperature can never rise into the danger zone. The latter alternative would be inefficient, and yet when two coils or heat exchange sections are located in heat exchange with hot products of combustion a major problem of control is presented since a change in the heating relationship as may be required to maintain the outlet temperature of the steam in one coil at a desired value will, of course, change the outlet temperature of the steam from the other coil.

It is a further object of the present invention to provide a control system for a steam generator of the foregoing type in which there are independently controlled the outlet temperatures from coils disposed in heat exchange relation to the hot products of combustion.

In accordance with the present invention, it has been found that where the system to be controlled embodies two temperature or condition-varying elements where one of them affects both of the conditions to be regulated

in the same sense, and the other affects both of the conditions, one being affected in a sense opposite to that of the other, the magnitudes of the two conditions may be maintained at selected temperatures each of which may be changed independently of the other but both maintained at the newly selected temperatures which establish the control points.

As applied to a boiler or steam generator with superheater coils in one section receiving hot gases and products of combustion from the fire chamber and with a reheater coil in another section likewise receiving the products of combustion from the fire chamber, one condition-varying element comprising means for recirculating hot products of combustion will affect both steam temperatures in the same sense, while the second condition-varying element, namely a damper control for regulating the division of hot products of combustion as between the superheater coils and the reheater coils, will affect both steam temperatures in an opposite sense.

Further in accordance with the invention, one condition-varying element, such as the output of the recirculator for the hot combustion products under the control of a damper, is placed under the control of means operable in response to changes in the algebraic sum of the magnitudes of the two conditions, i. e., the respective steam temperatures. The control means, of course, operates the condition-varying element in a direction and by an amount to maintain the algebraic sum at approximately a predetermined value. There is also provided a second control means operable in response to difference between the magnitudes of the two conditions, again the respective steam temperatures, for operating the second condition-varying element (the damper control) in a direction and by an amount to maintain a desired relationship between the magnitudes of the two conditions. Thus, in one application of the invention, there is provided independent control of the temperature at the outlet of the superheater section and the temperature at the outlet of the reheater section.

It is to be understood that the present invention is of general application to systems in which there are present a condition-varying element affecting two conditions in the same sense and a second condition-varying element affecting them in opposite sense.

For further objects and advantages of the invention and for a more detailed description, reference is to be had to the following description taken in conjunction with the accompanying drawings, in which:

Fig. 1 diagrammatically illustrates the invention embodied in an electrical control system for a steam boiler;

Fig. 2 illustrates the invention as embodied in a pneumatic control system for a steam boiler;

Fig. 3 diagrammatically illustrates the structure used for selecting or predetermining the control point; and

Fig. 4 is a graph explanatory of the operation of one embodiment of the invention.

Referring to the drawings, the invention in Fig. 1 has been illustrated as applied to a steam boiler 10 in which hot combustion gases from a fire chamber 11, shown in Fig. 2 with suitable arrays of fuel burners 12 and 13, flow through a passage 15 above a bridge wall 14. From the passage 15 the gases, Fig. 1, pass downwardly over a secondary superheater 16. Steam is delivered to superheater 16 from a divided primary superheater including sections 17a and 17b. Steam flow is from the steam drum (not shown) as by one or more pipes 18 through the two primary superheater sections 17a and 17b, the secondary superheater section 16 and by way of a pipe 19 to the high-pressure section 20 of a steam turbine 21. The steam with reduced temperature is discharged from the high-pressure section 20 and flows by way of pipe 23 to the reheater section 24 of furnace 10. After

elevation of the temperature of the steam it is discharged by way of pipe 25 into the second section 22 of the turbine 21. Additional sections (not shown) for the turbine will ordinarily be provided.

It will be observed that the secondary superheater section 16 is exposed to all of the hot products of combustion flowing through the passage 15 and downwardly to a passage 26 which leads to a stack (not shown). The hot gases and products of combustion then divide between the separate compartments or passages in which the steam heating sections 17a, 17b and 24 are respectively located. These separate compartments are formed by heat refractory baffles 27 and 28, and the division of the gases and hot products of combustion is under the control of suitable flow-controlling elements shown as dampers 31, 32 and 33. The dampers may be operated in any suitable manner.

When the condition-regulating means in the form of dampers 31 and 32 are moved in a passage-closing direction a greater proportion of the combustion gases flows through the central passage, and when the dampers 31 and 32 are moved in the opposite direction a greater proportion of the combustion gases will flow through the respective passages and less through the central passage. As shown in Fig. 1, the division of the gases between the three sections is regulated with substantially uniform pressure drop as between passages 15 and 26 by reason of the fact that when a control lever 34 is rotated, as by links 35 and 36 under the control of a motor 37, it moves dampers 31 and 32 in a passage-closing direction and it moves damper 33 in a passage-opening direction.

From the above description it will be seen that the outlet temperature of the steam from sections 17a, 17b and 16, as measured for example by a thermocouple 41, as well as the outlet temperature of the steam from section 24, as measured in pipe 25 by a thermocouple 42, will change with a change in volume of products of combustion flowing from passage 15 to passage 26. Those temperatures (other conditions remaining constant) will also change with change in temperature of the hot products of combustion. The relative temperatures of the outlet steam in pipes 19 and 25 may be regulated by changing the division of the hot products of combustion as between the central passage and the outside or flanking passages.

In accordance with the present invention, it has been found that the outlet temperatures, as in pipes 19 and 25, may be maintained within reasonably close limits at selected values by regulating the position of the dampers to vary the division of the hot gases as between sections 17a, 17b and section 24, and by regulating the heat content of combustion gases flowing from passage 15 to passage 26 by suitable control of a recirculating means. The heat content of gases flowing through heating sections 17a, 17b and 24 per unit time, may be varied in any suitable manner, as by regulating the position of a flow-controller or damper 45 disposed in a passage 46 forming the inlet to recirculating fan 47 connected to a discharge pipe 48 for return of flue gases to the fire chamber 11, as shown in Fig. 2. While the speed of the recirculating fan may be varied to control the volume of recirculated gases, normally the speed is constant and the positioning of damper 45 is used to change or control to the desired degree the regulation of the amount of recirculated gases and thus the heat content of the flue gases which flow from passage 15 to passage 26.

The manner in which the total heat content of gases entering the heating sections by way of passage 15 is regulated in accordance with the algebraic sum of the steam temperatures as measured by thermocouples 41 and 42, and the manner in which the division of the gases as between the several passages is determined by

the difference between said two temperatures, will now be explained in detail.

The temperature of the steam in outlet pipe 19, as detected by the thermocouple 41, may be measured in any suitable manner as by a potentiometric network 50 including a battery 51, a variable resistor 52, fixed resistors 53 and 54 and a slidewire resistor 55. By reason of relative movement provided between a contact 55a and slidewire resistor 55 the voltage developed by the thermocouple 41 is opposed by a voltage or potential difference developed across a fraction of the slidewire resistor 55. The relative adjustment to produce null balance may be effected manually or automatically as by the mechanical relay system of Squibb Patent No. 1,935,732, or by a high-speed electronic balancing system, such as described in Williams Patents Nos. 2,113,164 and 2,367,746.

As shown in Fig. 1 a difference or error voltage in the measuring circuit is applied to an amplifier 56 which controls one winding 57a of a motor 57, while the other winding 57b is energized from any suitable source of alternating-current supply. The motor, in accordance with the output of amplifier 56, is energized to drive, through suitable mechanical connections indicated by the broken line 58, the contact 55a to reduce to zero the unbalance or error voltage in the measuring circuit. At the same time it adjusts the position of a pen-index 59 relative to a scale 60 and a chart 61 driven at uniform speed by any suitable means such as by a synchronous motor 62.

In the same manner the temperature as indicated by thermocouple 42 is applied to a measuring circuit including potentiometric network 63 having a slidewire resistor 64 and a relatively adjustable contact 64a. The measuring system includes an amplifier 65 which controls the energization of one of the motor windings of motor 66, the other motor winding being connected to a suitable source of alternating-current supply, as illustrated. The temperature of the steam in line 25 is indicated by the pen-index 67 on scale 68 and is recorded on chart 69.

Control of the recirculating means by the positioning of damper 45 in accordance with the sum of the two temperatures detected by thermocouples 41 and 42 is achieved by unbalancing a balanceable system, as by adjustment of circuit elements or variable impedances shown as comprising contact 71a and its associated slidewire resistor 71 relatively movable in accordance with change in position of pen-index 59, a mechanical connection 73 illustrating the drive for contact 71a; and by relatively adjusting the contact 72a and slidewire resistor 72 as by mechanical connection 74 in accordance with the positioning of the pen-index 67. The slidewires 71 and 72 together with their shunting resistors 75 and 76 are connected in a balanceable control network which also includes resistors 77-80, a source of potential such as a battery 81, and an adjustable rheostat 82. The output potential from the control network as developed by the contacts 71a and 72a is opposed by a voltage or potential difference E_3 developed by a control network 85 including a source of supply, as battery 86, a slidewire resistor 87 with relatively adjustable contact 87a driven by a motor 88. The control network also includes a reset resistor 89, a reset capacitor 90, a pair of resistors 91 and 92, a rate resistor 93, a rate capacitor 94 which may have in series with it a resistor 95. In response to an unbalance voltage of one polarity or the other between contacts 71a and 72a the motor 88 through conventional means is energized for rotation in the forward or reverse direction to adjust, by way of mechanical connection 96, the damper 45 and the contact 87a, the direction of rotation for a given polarity of unbalance voltage being such as to return the sum of the two temperatures 41 and 42 to a predetermined value.

As fully explained in Davis Letters Patent No.

2,666,170, dated January 12, 1954, and No 2,688,717, dated September 7, 1954, the motor 88 is energized in direction and at a speed to maintain the voltage or potential difference E_3 equal and opposite to the potential difference (E_1) between slidewire contacts 71a and 72a. Accordingly, if the potential difference E_1 be other than zero the motor 88 will be energized to maintain movement of slidewire contact 87a for continued flow of current through resistor 89 and at least in part into or out of reset capacitor 90. Thus, reset action is introduced into the operation of the control network 85. The voltage difference across resistor 89 is attenuated by rate resistor 93 when there is change in the current flow through resistor 89 since under that condition current will flow by way of resistor 95 into or out of capacitor 94. By reason of the attenuation, the rate of movement of contact 87a will be greater when the rate of change of potential between contacts 71a and 72a is high than when it is low. Thus, the control network 85 includes a rate control action. In addition to the rate and reset actions the control system 85 also includes proportional action by reason of the follow-up adjustment of slidewire contact 87a by motor 88 in response to a potential difference between contacts 71a and 72a. The magnitude of the adjustment of contact 87a will include a component proportional to the extent of unbalance (the proportional action), a component due to the reset action, and a component due to the rate action.

It is to be understood the present invention is applicable to systems in which there is provided any desired combination of rate, reset and proportional action.

Assuming now that the sum of the temperatures as detected by thermocouples 41 and 42 exceeds a predetermined desired value, the motor 88 adjusts damper 45 until the heat content of products of combustion flowing between passages 15 and 26 decreases by an amount which lowers both temperatures to bring or to maintain their sum to its predetermined value. When their sum decreases below the desired and predetermined value, the converse action takes place and the damper 45 is adjusted to increase the flow of combustion products recirculated by fan 47 to increase said temperatures.

The desired temperature for the steam in line 19 as detected by thermocouple 41 may be selected by bodily moving slidewires 71 and 123 relative to their associated contacts 71a and 123a. In practice, it is generally more convenient for the motor to drive the disk which carries the slidewire and to have the associated contact stationary. In the diagrammatic drawing of Fig. 1, the slidewire contacts have been shown as movable and the same arrangement has been illustrated in the diagrammatic sketch of Fig. 3 in which the slidewires 71 and 123 are shown as supported by gears carried by a shaft 117 which is normally stationary but which through the operation of one or more gears 118a and 118b may be rotated as by a knob 119 to vary the position of each slidewire relative to the contacts 71a and 123a which are rotated by the motor 57. The knob 119 is referred to as a control-point setter and it may be arranged to drive an index 59a relative to the scale 60 to show in association with the pen-index 59 the predetermined temperature to be maintained for the outlet steam in line 19. An arrangement such as shown in Ross et al. Patent No. 2,096,064 may be utilized, where the shaft 10 of Fig. 2 of that patent would be driven by the motor 57 of accompanying Figs. 1 and 3 where the disks 25 of the patent correspond with the gears carrying the slidewires 71 and 123. The control-point setter or manually operating element of the patent would then relatively adjust the slidewire positions with respect to shaft 10.

Returning to Fig. 1, it will be seen that if slidewires 71 and 123 are bodily moved relative to their associated contacts, the resultant unbalance voltages will respectively produce energization of motors 88 and 37. If the control point temperature is lowered, the motor 88 will rotate in a direction to move damper 45 in passage-

closing direction. Thus the quantity of hot combustion products passing in heat exchange with sections 16, 17a, 17b and 24 will be decreased. However, motor 37 will be energized in a direction to move dampers 31 and 32 in passage-closing directions and dampers 33 in a passage-opening direction. The effect will be to lower the temperature in line 19 but by increasing the proportion of gas flow through section 24 there is maintained therein the same rate of heat absorption and thus the temperature of the steam in line 25 is unchanged. In this way the temperature of the steam in line 19 will be lowered as determined by the control-point setter without change of the temperature of the steam in line 25.

In similar manner, a control-point setter of the same type as shown in Fig. 3 is provided for predetermined the temperature of the steam in line 25. That control-point setter is associated with slidewires 72 and 124 bodily to move them relative to their associated contacts 72a and 124a. The unbalance voltage in network 84 resulting from a selection of a higher temperature produces energization of motor 88 to move damper 45 in a passage-opening direction to increase the flow of hot combustion products while the unbalance voltage from network 121 energizes motor 37 to move dampers 31 and 32 in passage-closing direction and dampers 33 in a passage-opening direction. Thus the rate of heat absorption in section 24 is increased while the rate of heat absorption in sections 17a and 17b is decreased by amounts adequate to maintain the same overall rate of heat absorption in section 16 plus that in sections 17a and 17b. Thus it will be seen that any selected outlet temperatures for the steam in pipes 19 and 25 will be maintained by the system, the selected output temperatures then establishing the predetermined sum and difference temperatures departure from which produces unbalance of the balanceable networks.

If desired, an additional control factor may be provided in manner generally set forth in said Davis Patent No. 2,688,717, the example shown in Fig. 1 including manometer lines or draft tubes 100 and 101 connected to a tilting U-tube manometer 102 mounted upon a lever arm 103 supported for rotation by a pivot 104. By reason of the difference in pressure detected by tubes 100 and 101, the fluid within the U-tube, such as mercury, is caused to assume a difference in elevation in the two legs of the tube. Lever arm 103 moves core members 105 and 106 relative to the primary windings 107 and 108 energized from a suitable source of alternating-current supply. A secondary winding 109 applies to a full-wave rectifier 110 a voltage whose amplitude varies with the position of core 105 between the coils 107 and 109. A fraction of the rectified output is applied by way of a slidewire 111 and conductors 112 and 113 to the control network 85 and in series between the movable contact 87a and the circuits including conductor 114 and resistor 89. Thus, the additional control action introduced into the network 85 depends upon a change in value of the pressure difference, between the pressure at the inlet of the tube 100 and that at the inlet of the tube 101.

By locating the open ends of the manometer tubes 100 and 101 in the draft passage 115, Fig. 2, downstream or near the stack from the inlet to the recirculating fan 47, as on opposite sides of an air preheater or economizer section 116, the manometer tube 102 will respond to the rate of flow of combustion gases. The flow rate, the total quantity of gases passing to the stack per unit time, in turn depends upon the rate of fuel combustion (assuming related proper adjustment of combustion air). A change in the amount or quantity of flue gases will provide an action which will anticipate the effects of such a change on the steam temperatures. This will be obvious if it be assumed that the amount of gases passing through the stack suddenly decreases. Such a decrease will mean each of, and the algebraic sum of, the temper-

atures of the steam flow in lines 19 and 25 will decrease if no further corrective action be introduced. However, the voltage output at the slidewire 111 resulting from operation of the manometer 102, introduces a potential difference in control network 85 which is effective to energize the motor 88 in a direction to open damper 45 for increased recirculation of combustion gases, the effect being to anticipate the expected decrease in temperature and thus to prevent its realization and to diminish the degree of temperature fall which would otherwise be realized.

By means of a balanceable system such as a control network 120 and a potentiometer network 121 of the same general type as control network 85 and potentiometric network 84, the motor 37 under the control of an amplifier 122 adjusts the dampers 31, 32 and 33 in response to the difference between the temperatures of the steam flow in lines 19 and 25. Thus, the motor 57 at the time it adjusts contact 71a of network 84 also adjusts a contact 123a of slidewire 123. Similarly, at the time contact 72a is adjusted the motor 66 adjusts contact 124a relative to slidewire resistor 124. The difference in operation between the two networks is symbolically illustrated by the cross-over lines of network 84 as compared with network 121. For example, in the former, with contacts 71a and 72a moving toward the left and in the direction of the low temperature ends of the respective slidewires 71 and 72, it will be seen an error signal of increasing magnitude will be developed. This will be made clear by arbitrarily assumed values. With the parts in their illustrated positions, it can be assumed that between the point 125 (directly connected to the negative pole of battery 81) and contact 71a there is a potential rise of 2 volts. There will also be a rise in potential between point 125 and contact 72a of 2 volts. The difference E_1 between the two potentials is, of course, zero. If now contact 71a is moved to the left toward the low temperature end of slidewire 71, the potential rise between point 125 and contact 71a will be decreased. If the potential difference at the new position be 1 volt, it will be seen that with an adjustment of contact 72a toward the high end of the slidewire marked "H" by an amount to reduce the potential rise from point 125 to 1 volt, the difference, E_1 will again be zero. Thus, the output or error voltage appearing between contacts 71a and 72a will remain unchanged though the temperature of the steam in line 19 decreased with a corresponding increase of temperature of the steam in line 25. In both cases the sum of the temperatures of the steam in lines 19 and 25 remained the same. Thus network 84 responds to change in the sum of the temperatures of the steam in lines 19 and 25. However, if the sum of the two temperatures changes and in a direction to produce adjustment of contacts 71a and 72a in the same direction, as for example by movement toward the high ends of the slidewires, the following will illustrate the action in terms of additional assumed values.

If the potential rise between point 125 and the new position of contact 71a be increased to 3 volts, the movement of contact 72a toward the high end will decrease the potential difference to 1 volt, and thus the error signal will be the difference between 3 volts and 1 volt, namely, 2 volts.

In the control system 120 the motor 37 operates the follow-up element or slidewire contact 120a for the proportional action; and the motor 88 of system 85 similarly moves slidewire contact 87a.

In the network 121 movement of contact 123a toward the left and toward the "low" end of slidewire 123 will reduce the potential between point 125a and contact 123a. However, movement of contact 124a toward the right and toward the high side will increase the potential difference. If the reduction in the first case reduces the potential difference between point 125a and contact 123a to 1 volt and the increase in temperature as detected

by thermocouple 42 increases the potential difference between point 125a and contact 124a to 3 volts, the error signal will be 2 volts. Thus network 121 responds to a change in the difference between the temperatures in lines 19 and 25.

The network 120 includes a reset resistor 89a, reset capacitor 90a, and a rate capacitor 94a. Thus, the difference-network produces a control action including proportional, rate, and reset components of control. The network also includes a component developed by manometer 102 by way of output winding 130, full-wave rectifier 131, slidewire 132, and conductors 133 and 134 which introduces the additional anticipatory control into control network 120 in manner already described in connection with network 85.

The polarity of the anticipatory voltage developed between conductors 133 and 134 will be selected depending upon the particular characteristics of the steam generator. In some cases it will be desirable that the anticipatory action shall produce rotation of motor 37 in a direction to operate dampers 31 and 32 in passage-closing direction, while moving the dampers 33 in a passage-opening direction. The action, in any case, will be such that with an assumed decrease in the flow of the gases and products of combustion to the stack, the redistribution of the gas flow as between the superheater sections 17a and 17b and the re heater section 24 will maintain the difference in temperature of the steam flowing in lines 19 and 25 at the desired predetermined values, at least more so than if the anticipatory control were not included as a part of the system.

In summary, the fluid-heating system of Fig. 1 provides for the maintenance at a selected value of the temperature of the fluid stream in line 19 at a predetermined value, while at the same time maintaining at a predetermined value the temperature of the fluid in line 25. The foregoing is accomplished by controlling the heat exchange rates as between the volume or quantity of a condition-changing agent such as the heating agent comprising flue gases, recirculation of which is regulated in accordance with the sum of the temperatures of said fluid or vapor streams and the division of said agent relative to said streams as by controlling the division of flow of the combustion gases in heat exchange with the two streams in accordance with the difference between their said temperatures. The end result is the delivery at uniform temperature of the steam supplied by way of lines 19 and 25 to the two sections of the turbine 21 which is shown driving, for example, an electrical power generator 135.

It is to be understood that other features of control will normally be provided in the operation of the boiler, such as a master control responsive to steam pressure in the steam drum, all as described in Bristol Letters Patent No. 2,657,347, dated October 27, 1953, and it is to be further understood that the method of the present invention may not only be performed manually by the electrical system of Fig. 1, but also by other instrumentalities, such as the pneumatic system illustrated in Fig. 2, and it is to be understood the invention is applicable to cooling systems and other conditions whose magnitudes are affected in ways analogous to the steam temperatures above described.

In the description of the invention thus far presented, there was an implied assumption that the output voltages (between contacts 71a and 72a and between contacts 123a and 124a) of networks 84 and 121, respectively, changed by equal amounts with equal changes in the sum of the temperatures detected by thermocouples 41 and 42 and with equal changes in the difference between the temperatures detected by them. However, the assumed equality in output for the respective changes in the sums and differences of the temperatures detected will be the preferred operation for those cases in which the respective temperatures in lines 19 and 25 will be maintained

by the equal adjustments produced by motors 88 and 37.

In many cases the rate of heat absorption in the re-heater section 24 may differ from the rate of heat absorption in the steam superheater sections 16, 17a and 17b, and thus the response of the sum and difference control networks and of the respective motors 88 and 37 controlled by them should be different when the temperature detected by thermocouple 41 changes by a given amount than when the temperature detected by the thermocouple 42 changes by the same amount. The additional flexibility provided in accordance with the present invention as embodied in the system of Fig. 1, has already been mentioned in the reference to the fact that any change in the rate of flow or quantity of combustion gases passing over the superheater section 16 produces operation of the motor 37 to correct for the added or decreased heat absorption by section 16.

The foregoing requirement is met by providing the slidewires 71 and 72 with adjustable shunting resistors 75 and 76 and the slidewires 123 and 124 are similarly provided with adjustable shunting resistors 75a and 76a. By adjusting shunting resistor 75 to have a value differing from shunting resistor 76 and assuming slidewires 71 and 72 to have equal resistance values, the degree of adjustment of motor 88 for a given change in temperature detected by thermocouple 41 may be made widely different from the adjustment produced by a like change in the temperature of the thermocouple 42. Similarly, by adjusting shunting resistors 75a and 76a to have differing values, the degree of adjustment of dampers 31-33 produced by motor 37 may be widely different for a given temperature change by thermocouple 41 than for a like temperature change of the thermocouple 42.

Further flexibility is provided by varying the resistance values of rheostats 82 and 82a to provide a different output from one of the networks 84 and 121 than the other for a given change in temperature and corresponding movement of slidewire contacts 71a and 123a. For example, if the potential difference across slidewire 123 is made greater by increasing the current flow through the adjustable resistor 82a, the follow-up movement of the follow-up contact 120a relative to its slidewire will be increased and will require a greater movement of motor 37 to move that contact to the network balancing position. Thus, the throttling range for the control of motor 37 may differ from the throttling range for the control of motor 88.

Though the system has great flexibility by reason of the additional features, it is again emphasized that the network 84 continues to function in response to the sum of the temperatures detected by thermocouples 41 and 42 and the network 121 continues to respond to the difference between those temperatures, and that when the sum and difference networks have been referred to in the claims the descriptive language is intended to be broad enough to include the modifying features just described.

In some applications of the invention, it may be desirable to adjust the network 121 to have operating characteristics as shown by the straight lines 137 and 136R on the graph of Fig. 4 plotted with temperature as abscissae and output voltage or potential difference as ordinates. Thus, with a change in temperature of thermocouple 41 the potential difference between contact 123a and point 125a of the networks will vary in accordance with graph 137. On the other hand, the potential between contact 124a and the point 125a will vary at a different rate and will be represented by a line or graph of different slope as indicated by the line 136R. As previously explained, the voltage output of network 121 between contacts 123a and 124a will be the difference between two voltages just identified. With the temperatures in lines 19 and 25 at the set points indicated on the graph of Fig. 4 respectively at T_{41} and T_{42} , the voltage between point 125a and the contact 123a is shown as the ordinate

of graph 137 at T_{41} , and that the voltage between point 125a and contact 124a is shown as the ordinate of graph 136R at T_{42} , the two voltages being of equal magnitude. Since they are opposed as between contacts 123a and 124a there is zero output from network 121.

To illustrate the changed operation provided by the shunts 75a and 76a for the slidewires, it will now be assumed that the temperature of thermocouple 42 is increased to the value T_{42a} and that the temperature of thermocouple 41 is increased to the value T_{41a} . While the temperature of thermocouple 41 has increased to greater degree than the temperature of thermocouple 42 with an increase in their difference between them, nevertheless, the network 121 has zero output by reason of the fact that the change of voltage per degree change of temperature is greater for the thermocouple 42, graph 136R, than it is for the thermocouple 41, graph 137. Thus, the operation of the difference network 121 has been modified so that it produces an output voltage when the difference between the steam temperatures in lines 19 and 25 attains values requiring damper adjustments; within the limits established by a particular installation adjustments will not be needed since compensating factors resulting from the particular heating characteristics of the superheater sections and the heating characteristics of the reheat section themselves tend to keep the steam temperatures at the control or set points.

The foregoing flexibility likewise applies to the "sum" control network 84 where the graph 136R of Fig. 4 represents changes in potential difference between the point 125 and the contact 72a with temperature change, while the graph 137S represents changes in potential difference between point 125 and slidewire contact 71a with change in temperature of thermocouple 41. At the temperature T_{41} for thermocouple 41 and the temperature T_{42} for the thermocouple 42, it will be obvious by reference to graphs 136R and 137S that the voltage outputs are equal. Because they are equal and are opposed as between contacts 71a and 72a, the output of network 84 is zero and the two temperatures are at the set points as before. If it now be assumed that the temperature of thermocouple 42 is increased to T_{42a} and that of thermocouple 41 has decreased to T_{41b} , and by the same amount as the increase, the sum of the two will be changed over its previous value but the voltage, graph 136R, at T_{42a} has the same value as the voltage indicated on graph 137S at the temperature T_{41b} . The response of the network 84 has been somewhat modified to take into account the variable heating characteristics of the reheat and superheater sections. Nevertheless, it continues to function whenever the sum differs by an amount which is not compensated for by the inherent characteristics of a particular heating system. The graphs of Fig. 4 are to be taken as illustrative of the flexibility of the system and the manner in which it may be readily adapted to a wide variety of applications including steam generators of greatly differing design.

Referring to Fig. 2, the invention has been shown as applied to balanceable systems of quite a different type but to a fluid heating system the same as in Fig. 1. In fact certain details of the steam generator of Figs. 1 and 2 have already been described. In Fig. 2, the secondary superheater is diagrammatically shown at 16 with similar diagrammatic showing of one primary superheater 17a and the reheat coil 24. Thermocouples 41 and 42, in association with measuring systems 140 and 141 of the same type as illustrated and described in the embodiment of Fig. 1, indicate on their respective scales and charts 140a, 140b and 141a, 141b, the respective temperatures of the steam flow in lines 19 and 25. The motor 57 of network 140 operable in accordance with the temperature in line 19 adjusts a control screw 142 to change the position of a baffle 143 and thus varies the air or fluid pressure developed by a booster 144 in a line 145. For a detailed disclosure of the operation of the illustrated

pneumatic system, reference is to be had to McLeod Patent No. 2,507,606, the booster 144 corresponding with the booster 56 of that patent, and the pressure in line 45 corresponding with the pressure in line 68 of said patent. Instead of the reset bellows 46 of said patent, there is shown in Fig. 2 a spring 146, which is preferably adjustable. While the system may include a reset control component and a rate component in manner disclosed in said patent, the spring 146 has been provided for a system with only proportional action present.

As explained in said McLeod patent, the pressure in line 145 will vary in accordance with the change in the temperature detected by thermocouple 41. In a similar manner, the motor 66, whose energization is under the control of the potentiometer network 141 and amplifier 65, will adjust the control screw 142a to position the baffle 143a relative to the associated nozzle. Through the action of the booster 144a the pressure in line 147 will vary with change in the temperature detected by thermocouple 42.

The pressure in line 147 is transmitted by way of line 148 to a bellows 149 acting on a pivoted lever 150 in a direction tending to move it counterclockwise against the opposing pressure of a spring 151. A bellows 152 receiving the pressure from line 145 tends to rotate the lever 150 in the same counterclockwise direction to change the position of that lever relative to nozzle 153 which, through a booster 144b, establishes a pressure in line 154 which varies in accordance with the sum of the pressures in lines 147 and 145. Thus, the pressure in line 154 will vary as the sum of the temperatures of the steam flow in lines 19 and 25. A follow-up bellows 155 responsive to the output pressure in line 154 tends to rotate the lever 150 in a clockwise direction and provides proportionality between the pressure 154 and the sum of the pressures in lines 145 and 148.

The pressure in line 154 is applied to a pneumatic operator 156 which may be of the same type as diagrammatically illustrated in said McLeod patent for the operation of the valve identified in that patent by the reference character 11. The pneumatic actuator 156 positions the damper 45 in the inlet pipe to the recirculating fan 47.

It will be observed that the pressures in lines 145 and 147 are respectively applied to bellows 157 and 158, which with respect to a lever 159 develop forces tending to rotate it in opposite directions. Thus, the position of pivot lever 159 relative to a nozzle 160 will depend upon the difference in the magnitude of the two pressures applied to bellows 157 and 158. The spring 161 opposes a proportional bellows 162, and a booster 144c establishes in a line 162a a pressure proportional to the difference between the pressures applied to bellows 157 and 158. The pressure in line 162a is applied to a pneumatic actuator 163 of the same type as actuator 156 and operates to position the lever 34 to position the dampers 31, 32 and 33 of Fig. 1, only the dampers 32 being shown in Fig. 2.

From the foregoing description it will be seen that apparatus has been provided for carrying out the invention both by the balanceable networks or electrical systems of Fig. 1 and by the balanceable systems of Fig. 2 shown as of the pneumatic type. In accordance with both systems the magnitudes of two conditions are controlled and maintained to selected values by varying the setting of two condition-varying elements where one of the latter affects both of the conditions in the same sense and where another of them affects them in opposite sense.

Variation in the operation of the "sum" and "difference" controllers of the pneumatic system of Fig. 2 may be desired for the same reasons discussed in connection with the slidewire shunting resistors of Fig. 1. As explained in said McLeod patent, the nozzles associated with baffles 143 and 143a are adjustable to vary the throttling ranges. By making the springs 146, 151, 161

and 165 adjustable, further flexibility is provided. Similarly the extent of movement of each control screw, 142, 142a, for a given change in temperature may be made to differ by providing different gear or driving ratios between them and their respective motors 57 and 66.

It is again emphasized that while the invention has been shown as particularly applicable to temperature control systems, it is not to be limited thereto, the scope of the invention being commensurate with that of the appended claims.

What is claimed is:

1. A control system for maintaining the magnitudes of two conditions at predetermined values by maintaining both the magnitude of their sum and the magnitude of their difference at predetermined values, comprising means including two condition-varying elements a first of which is operable concurrently to vary the magnitudes of said conditions in opposite senses and the second of which is operable concurrently to vary the magnitudes of said conditions in the same sense, first and second condition-sensitive means respectively responsive to the magnitudes of said two conditions, a balanceable summing system which is balanced when said sum is at a predetermined value, a balanceable difference system which is balanced when said difference is at a predetermined value, each of said balanceable systems having a first adjustable element and a second adjustable element respectively affecting the balance of said systems, means responsive to said first condition-sensitive means for concurrently actuating said first adjustable element in each of said systems, means responsive to said second condition-sensitive means for actuating said second adjustable element in said summing system for producing in conjunction with said adjustment of said first element an unbalance of said summing system upon deviation of the sum of the magnitudes of said conditions from said predetermined value and for concurrently actuating said second adjustable element in said difference system for producing in conjunction with said first element in said difference system unbalance of said difference system upon deviation of the difference between said two conditions from said predetermined value, each of said systems including an adjustable system-balancing element, a first actuating means responsive to the unbalance of said summing system in one direction for actuating one of said condition-varying elements to change in the same direction the magnitudes of said conditions for changing the sum of said magnitudes to approach said predetermined value of said sum, a second actuating means responsive to the unbalance of said difference system for concurrently actuating the other of said condition-varying elements for concurrently changing the magnitudes of said conditions in opposite directions to change the difference between said magnitudes in a direction to approach said predetermined value of said difference, each of said actuating means having a connection for adjustment respectively of said system-balancing elements in said systems in directions to restore balance of each of them.

2. A control system for maintaining the magnitudes of two conditions at predetermined values by maintaining both the magnitude of their sum and the magnitude of their difference at predetermined values, comprising means including two condition-varying elements, a first of which is operable concurrently to vary the magnitudes of said conditions in opposite senses and the second of which is operable concurrently to vary the magnitudes of said conditions in the same sense, first and second condition-sensitive means respectively responsive to the magnitudes of said two conditions, a balanceable electrical summing network which is balanced when said sum is at a predetermined value, a balanceable electrical difference network which is balanced when said difference is at a predetermined value, each of said balance-

able networks having a first adjustable impedance element and a second adjustable impedance element respectively affecting the balance of said networks, means responsive to said first condition-sensitive means for concurrently adjusting said first adjustable impedance element in each of said networks, means responsive to said second condition-sensitive means for adjusting said second adjustable impedance element in said summing network for producing in conjunction with said adjustment of said first impedance element an unbalance of said summing network upon deviation of the sum of the magnitudes of said conditions from said predetermined value and for concurrently adjusting said second adjustable impedance element in said difference network for producing in conjunction with said first impedance element in said difference network unbalance of that network upon deviation of the difference between said two conditions from said predetermined value, each of said networks also including an adjustable network-balancing impedance element, a first actuating means responsive to the unbalance of said summing network in one direction for actuating one of said condition-varying elements to change in the same direction the magnitudes of said conditions for changing the sum of said magnitudes to approach said predetermined value of said sum, a second actuating means responsive to the unbalance of said difference network for concurrently actuating the other of said condition-varying elements for concurrently changing the magnitudes of said conditions in opposite directions to change the difference between said magnitudes in a direction to approach said predetermined value of said difference, each of said actuating means having a connection for respectively adjusting said system-balancing impedances in said networks in directions to restore balance of each of them.

3. In a fluid heating system having separate flow passages for a heating agent, fluid-conducting heating sections disposed in each of said passages for maintaining the fluid outlet temperatures of the respective sections at predetermined values, the combination of two adjustable flow-controlling elements for said agent, a first of said flow-controlling elements being adjustable to change the quantity of said heating agent passing through said separate flow passages to change in the same direction said fluid outlet temperatures, and the second of said flow-controlling elements having structure disposed in reference to said passages adjustable for varying the division of said quantity of said heating agent between said sections to change said fluid outlet temperatures in opposite directions, a first control means including a balanceable electrical network with impedances respectively adjustable in response to said fluid outlet temperatures in direction and to extent which unbalances said network in accordance with the sum of said outlet temperatures for operating said first flow-controlling element for changing the quantity of said agent in a direction and by an amount to maintain said sum at a predetermined value, a second control means including a second balanceable network having impedances respectively adjustable in response to said fluid outlet temperatures in direction and extent which unbalances said network in accordance with the difference between said outlet temperatures for operating, concurrently with adjustment of said first condition-varying element, said second condition-varying element in a direction and by an amount to vary the division of said agent between said flow passages for maintaining at a predetermined value said difference between said outlet temperatures, whereby said fluid outlet temperatures are maintained at said predetermined values, and means responsive to changes in the quantity of said heating agent which occur independently of the effect of said first flow-controlling element for adjusting said first flow-controlling element in a direction to anticipate and to compensate for said change in said quantity.

4. In a fluid heating system having separate flow pas-

sages for a heating agent, fluid-conducting heating sections disposed in each of said passages for maintaining the fluid outlet temperatures of the respective sections at predetermined values, the combination of two adjustable flow-controlling elements for said agent, a first of said flow-controlling elements being adjustable to change the quantity of said heating agent passing through said separate flow passages to change in the same direction said fluid outlet temperatures, and the second of said flow-controlling elements having structure disposed in reference to said passages adjustable for varying the division of said quantity of said heating agent between said sections to change said fluid outlet temperatures in opposite directions, a first control means including a balanceable electrical network with impedances respectively adjustable in response to said fluid outlet temperatures in direction and to extent which unbalances said network in accordance with the sum of said outlet temperatures for operating said first flow-controlling element for changing the quantity of said agent in a direction and by an amount to maintain said sum at a predetermined value, a second control means including a second balanceable network having impedances respectively adjustable in response to said fluid outlet temperatures in direction and extent which unbalances said network in accordance with the difference between said outlet temperatures for operating, concurrently with adjustment of said first condition-varying element, said second condition-varying element in a direction and by an amount to vary the division of said agent between said flow passages for maintaining at a predetermined value said difference between said outlet temperatures, whereby said fluid outlet temperatures are maintained at said predetermined values, and means responsive to changes in the quantity of said heating agent which occur independently of the effect of said first flow-controlling element for applying to one of said networks a network unbalancing voltage for adjusting one of said flow-controlling elements independently of said predetermined values of said sum and of said difference.

5. In a fluid heating system having separate flow passages for a heating agent, fluid-conducting heating sections disposed in each of said passages for maintaining the fluid outlet temperatures of the respective sections at predetermined values, the combination of two adjustable flow-controlling elements for said agent, a first of said flow-controlling elements being adjustable to change the quantity of said heating agent passing through said separate flow passages to change in the same direction said fluid outlet temperatures, and the second of said flow-controlling elements having structure disposed in reference to said passages adjustable for varying the division of said quantity of said heating agent between said sections to change said fluid outlet temperatures in opposite directions, a first control means including a balanceable electrical network with impedances respectively adjustable in response to said fluid outlet temperatures in direction and to extent which unbalances said network in accordance with the sum of said outlet temperatures for operating said first flow-controlling element for changing the quantity of said agent in a direction and by an amount to maintain said sum at a predetermined value, a second control means including a second balanceable network having impedances respectively adjustable in response to said fluid outlet temperatures in direction and extent which unbalances said network in accordance with the difference between said outlet temperatures for operating, concurrently with adjustment of said first condition-varying element, said second condition-varying element in a direction and by an amount to vary the division of said agent between said flow passages for maintaining at a predetermined value said difference between said outlet temperatures, whereby said fluid outlet temperatures are maintained at said predetermined values, and means responsive to changes in the quantity of said heating agent which occur independently of the effect of said first flow-controlling element for adjusting said first flow-controlling element in a direction to anticipate and to compensate for said change in said quantity.

trolling element for applying to both of said networks unbalancing voltages for adjustment of both of said flow-controlling elements independently of said predetermined values of said sum and of said difference.

6. In a fluid heating system having separate flow passages for a heating agent, fluid-conducting heating sections disposed in each of said passages for maintaining the fluid outlet temperatures of the respective sections at predetermined values, the combination of two adjustable flow-controlling elements for said agent, a first of said flow-controlling elements being adjustable to change the quantity of said heating agent passing through said separate flow passages to change in the same direction said fluid outlet temperatures, and the second of said flow-controlling elements having structure disposed in reference to said passages adjustable for varying the division of said quantity of said heating agent between said sections to change said fluid outlet temperatures in opposite directions, a first control means including a balanceable electrical network with impedances respectively adjustable in response to said fluid outlet temperatures in direction and to extent which unbalances said network in accordance with the sum of said outlet temperatures for operating said first flow-controlling element for changing the quantity of said agent in a direction and by an amount to maintain said sum at a predetermined value, a second control means including a second balanceable network having impedances respectively adjustable in response to said fluid outlet temperatures in direction and extent which unbalances said network in accordance with the difference between said outlet temperatures for operating, concurrently with adjustment of said first condition-varying element, said second condition-varying element in a direction and by an amount to vary the division of said agent between said flow passages for maintaining at a predetermined value said difference between said outlet temperatures, whereby said fluid outlet temperatures are maintained at said predetermined values, and means responsive to changes in a characteristic of said heating agent which occur independently of the effect of either of said flow-controlling elements for applying to both of said networks unbalancing voltages for adjustment of both of said flow-controlling elements independently of said predetermined values of said sum and of said difference.

7. In a fluid heating system having separate flow passages for a heating agent, fluid-conducting heating sections disposed in each of said passages for maintaining the fluid outlet temperatures of the respective sections at predetermined values, the combination of two adjustable flow-controlling elements for said agent, a first of said flow-controlling elements being adjustable to change the quantity of said heating agent passing through said separate flow passages to change in the same direction said fluid outlet temperatures, and the second of said flow-controlling elements having structure disposed in reference to said passages adjustable for varying the division of said quantity of said heating agent between said sections to change said fluid outlet temperatures in opposite directions, a first control means including a balanceable electrical network with impedances respectively adjustable in response to said fluid outlet temperatures in direction and to extent which unbalances said network in accordance with the sum of said outlet temperatures for operating said first flow-controlling element for changing the quantity of said agent in a direction and by an amount to maintain said sum at a predetermined value, and a second control means including a second balanceable network having impedances respectively adjustable in response to said fluid outlet temperatures in direction and extent which unbalances said network in accordance with the difference between said outlet temperatures for operating, concurrently with adjustment of said first condition-varying element, said second condition-varying element in a direction and by an amount to vary

the division of said agent between said flow passages for maintaining at a predetermined value said difference between said outlet temperatures, whereby said fluid outlet temperatures are maintained at said predetermined values.

5 8. In a steam generator having separate flow passages for hot products of combustion, a steam superheater section and a steam reheat section respectively disposed in said passages and in heat exchange relation with said hot products of combustion and having adjustable control means for concurrently changing the heat input from said hot products of combustion to said sections and damper means for varying the division of the hot products of combustion between said sections, the combination of means for maintaining at predetermined values the respective exit temperatures of steam passing through said sections by maintaining the magnitude of their sum at a predetermined value and by maintaining the magnitude of their difference at a predetermined value, comprising first and second temperature-sensitive means responsive to the exit temperatures of the steam from said sections, a balanceable summing system, a balanceable difference system, each of said balanceable systems having a first adjustable element and a second adjustable element respectively affecting the balance of said systems, means responsive to said first temperature-sensitive means for concurrently actuating said first adjustable element in each of said systems, means responsive to said second temperature-sensitive means for actuating said second adjustable element in said summing system for producing 10 in conjunction with said adjustment of said first element an unbalance of said summing system upon deviation of the sum of the magnitudes of said conditions from said predetermined value and for concurrently actuating said second adjustable element in said difference system for producing 15 in conjunction with said first element in said difference system unbalance of said difference system upon deviation of the difference between said two conditions from said predetermined value, each of said systems including an adjustable system-balancing element, a first 20 actuating means responsive to the unbalance of said summing system in one direction for actuating said control means concurrently to increase the heat input to both of said sections and upon unbalance of said summing system in the opposite direction for actuating said control means 25 responsive to decrease said heat input to said sections, said actuating means having a driving connection for concurrently adjusting said system-balancing element of said summing system in a direction to restore balance of said summing system, and a second actuating means responsive to the unbalance of said difference system in one direction for actuating said damper means 30 concurrently to increase the heat input to one of said sections and to decrease the heat input to the other of said sections and operable in response to unbalance of said difference system in the opposite direction for decreasing the heat input to said one of said sections while increasing the heat input to the other of said sections, said damper means being actuated in a direction which relatively 35 changes the heat input to said sections in a direction to reduce departure of said difference between said steam temperatures from its said predetermined value, said second actuating means having a driving connection for concurrently adjusting said system-balancing element of said difference system in a direction to restore balance to said difference system, whereby upon deviation of either or 40 both of said steam temperatures from their predetermined values the deviating steam temperature is returned to its said predetermined value with a minimum change in the other steam temperature during the concurrent re-adjustments of said heat inputs to said sections by both 45 said actuating means.

70 9. In a steam generator having separate flow passages for hot products of combustion, a steam superheater section and a steam reheat section respectively disposed in said passages and in heat-exchange relation with said hot

products of combustion, change in the total quantity of combustion products which flows through said passages varying the heat inputs to said sections in the same direction and change in the division of flow of said products of combustion through said passages increasing the heat input to one of them while decreasing the heat input to the other of them, means for recirculating combustion gases to vary said quantity of said products of combustion flowing through said passages and damper means disposed in relation to said passages for varying said division between them of said products of combustion, the combination of a balanceable summing network and a balanceable difference network, each said network having a pair of adjustable circuit elements and each having a follow-up adjustable circuit element, means respectively responsive to the outlet steam temperatures of said superheater section and of said reheater section for respectively and concurrently adjusting said pairs of adjustable circuit elements for unbalancing said pair of networks, said pair of said circuit elements in said summing network being connected for unbalancing it in response to change in the sum of the magnitudes of said steam temperatures and the other of said pair of adjustable circuit elements being connected in the other of said networks for unbalancing it in response to change in the difference between the magnitudes of said steam temperatures, first control means responsive to the unbalance of said summing network for controlling said recirculating means for increasing said quantity of said products of combustion flowing

through said passages upon change in the unbalance of said summing network in one direction and for decreasing said quantity of said products of combustion upon change in the unbalance of said summing network in the opposite direction, said first control means being connected to adjust said follow-up circuit elements in said summing network in a direction to restore balance of said summing network, and a second control means responsive to the unbalance in one direction of said difference network for operating said damper means in one direction and responsive to the unbalance of said network in an opposite direction for operating said damper means in an opposite direction for varying said division between said passages of said products of combustion to increase the heat transfer to one of said sections and to decrease the heat transfer to the other of said sections, said second control means being connected to adjust said follow-up element in said difference network in a direction to restore balance to said difference network.
